FRAMING CHANNEL STRUCTURES

Harold G. Olson, Old Greenwich, Conn., assignor to The Bailey Company, Inc., Amesbury, Mass., a corporation of Massachusetts

Application December 8, 1955, Serial No. 551,848

6 Claims. (Cl. 189—76)

This invention relates to improvements in channel structures and more particularly to metallic channel structures for engaging around edge margins of sheet elements which may be panes of glass, or sheets and panels of other materials, which are to be mounted within a metallic frame for protectively supporting the sheet element as a window or panel in a building or for serving in the nature of a shipping crate, or the like, to protectively enclose the edge margins of one or more glass panes, panels, or the like. The invention provides an improved channel structure, for the mentioned general purposes, wherein channels of metal and of resilient cushioning material are combined and utilized in a novel manner to attain novel results and effects.

The invention is herein illustrated and described as it may be embodied in a window frame which may be of the jalousie or any other type, but it should be understood that the disclosed channel structure is not limited in utility to window frames but may be employed wherever it becomes necessary or desirable to protectively enclose edge margins of sheet elements as a permanent frame for single sheet elements of glass, or the like, or as a permanent or temporary protective frame for edge margins of a single sheet element, such as a structural panel, for example, or a plurality of such panels, grouped together for shipment.

The present invention contemplates a novel channel structure fabricated from elongated framing stock of simple construction, lengths of which may be cut whenever desired into suitable sections that need only be joined at their ends to provide without more a weather-proof and non-rattling support or protector for a glass pane, a panel, or a plurality of the panes or panels grouped together, as for shipment.

An object of the present invention is to provide framing stock of the foregoing type comprising telescoped channels, the outer one being composed of a relatively stiff resilient material such as sheet metal, and an inner one being composed of a relatively soft compliant material such as rubber, the channels being permanently connected by beads in the extremities of the legs of the outer channel which tightly pinch the extremities of the legs of the inner channel.

Another object of the present invention is to provide a channel structure comprising sections of framing stock of the foregoing type which are connected at their ends by specially designed angle bars, the arms of which extend between bight portions of two telescoped channels.

Other objects of the invention will in part be obvious and will in part appear hereinafter.

The invention accordingly comprises the product possessing the properties, features and relation of components which are exemplified in the following detailed disclosure, and the scope of the application of which will be indicated in the appended claims.

For a fuller understanding of the nature and objects of the invention, reference should be had to the following

2

detailed description taken in connection with the accompanying drawing wherein:

Fig. 1 is a front elevation of a window embodying the present invention;

5 Fig. 2 is a perspective view of a fragment of the window of Fig. 1 with portion broken away, and with parts in section, the section being taken along the line 2—2 of Fig. 1;

10 Fig. 3 is a perspective view of one of the corner components of the window of Fig. 1; and

Fig. 4 is a side elevation of a modified wrap-form of framing channel.

15 Fig. 1 illustrates a jalousie window 10 removably secured within a suitable frame 11 by a series of pivotable fasteners 12. Window 10 includes a glass pane 13 and four framing sections 14 secured at their mitered ends by four corner brackets 15.

20 Sections 14 are shown in detail in Fig. 2 as comprising an inner channel 16, a medial channel 17 and an outer channel 18. Inner channel 16, preferably, is composed of a relatively soft compliant material, for example, a rubberlike material such as natural rubber or neoprene, a synthetic plastic material such as polyethylene or nylon or a fibrous material such as felt or asbestos. Inner channel 16, which is designed to snugly engage the edges of pane 13, serves as a weather-proofing and shock absorbing seal or cushion. Medial channel 17 and outer channel 18 preferably are rolled into shape from suitable sheet metal blanks. Medial channel 17 is coextensive with

25 inner channel 16 so that its arms have the leverage and its bight portion the proximity to tightly grip and effectively support the edges of pane 13 with the inner cushioning and sealing channel 16 intervening between them. The legs of outer channel 18 are longer than the legs of medial and inner channels 17 and 16 so that the bight portion 30 of the outer channel is spaced from bight portions 21 and 22 of the medial and inner channels. Bight portion 20 is provided with a reentrant step having a horizontal portion 23 and a vertical portion 24, as viewed in Fig. 2. Vertical portion 24 preferably is provided with a strip 25 of soft compliant material which may be cork or any of the materials described above in connection with inner channel 16. Strip 25 serves as a weather-proofing and shock absorbing seal between sash 10 and frame 11.

35 40 45 Channels 16, 17 and 18 are permanently connected to each other without additional discrete components as follows. The extremities of the legs of channels 17 and 18 are reversely bent to provide beads 26, 26 and 27, 27. Associated beads 26 and 27 are shaped together to permanently interlock the outer two channels and at the same time to firmly pinch the extremities of the legs of inner channel 16. The beads additionally serve as guides to spread the legs of the composite channel when the edge of a glass pane is introduced.

50 55 60 65 70 The ends of sections 14 are connected by angle brackets 15 that have been stamped, cast or otherwise formed into the shape shown in Fig. 3. Each bracket 15 has two coplanar arms 30 and 31 which are provided, along their inner edges, with ridges 32 and 33 lying in planes perpendicular to the common plane of the arms. As will be seen in Fig. 2, the thickness of arms 30 and 31 is substantially the same as the distance between vertical portion 24 and the adjacent parallel portion of the longer leg of outer channel 18. Furthermore, ridges 32 and 33 are spaced from the outer edges of the arms by distances which permit ridge 32 to immediately underlie horizontal portion 23 of one framing section 14, and ridge 33 to immediately underlie horizontal portion 23 of an adjacent framing section 14, when the outer edges of the arms underlie the outermost portions of bights 20, 20 of the two sections. The arms and ridges of brackets 15 may be welded or otherwise secured to the reentrant step portions

and legs of the outer channels 18 of the two adjacent sections 14.

In practice, framing stock of the above description may be conveniently cut, in the factory or in the field, into sections which when joined by brackets of the above description provide a weather-proof and non-rattling sash for a glass pane of any chosen size. However, the cut sections may be joined together by any suitable means, and may be produced in sizes suitable for engaging over edge margins of various sheet elements for any of a variety of purposes, such as for protecting the edges of panels and the like during handling and shipping.

In the interests of economy, it sometimes may be desirable to produce the framing sections in continuous strip form with cut-out notches suitably spaced apart so that the strip may be wrapped around the edges of a pane or panel, or a plurality of grouped together panes or panels, and extend continuously around all four sides thereof. Fig. 4 shows such a continuous strip 14' which has been notched at predetermined spaced locations 34 where corner bends are to occur, with complementary end portions adapted to be brought together and secured at one corner of the frame. The 90° angular notches may be cut in the channels prior to their being assembled or after assembly. Corner brackets 15, or the like, at each of three of the corners may be loosely inserted at the time of bending the frame. Each of these brackets will be retained as a corner reinforcement by the right-angularly related sides of the frame extending from that corner. The bracket 15 at the fourth corner, where the mitre joint is to be effected, may have the opposite end portions welded or otherwise rigidly secured to it for strengthening the mitre joint. Obviously, all of the corner brackets may be welded or otherwise secured to the outer channels if this is considered desirable for strength at the corners.

Since certain changes may be made in the above product without departing from the scope of the invention herein involved it is intended that all matter contained in the above description and shown in the accompanying drawing, shall be interpreted in an illustrative and not in a limiting sense.

I claim as my invention:

1. Framing stock for engaging around edge margins of sheet elements, comprising a sheet metal outer channel and an inner channel of resilient cushioning material, the side walls of said inner channel being in relatively close general parallelism with the side walls of said outer channel, and the bottom wall of said inner channel being spaced from adjacent generally parallel wall portions of said outer channel, edge portions of the opposite side walls of said outer channel being rolled around and into gripping relation to edge portions of the side walls of said inner channel thereby to secure the said channels permanently together and to provide metallic edge beads which enclose the edges of said inner channel and which are resiliently spreadable for guiding edge portions of a sheet element into seated engagement within said inner channel.

2. Framing stock comprising an inner channel, a medial channel and an outer channel in telescoped relation, said inner channel being composed of compliant material, said medial channel and said outer channel being composed of rolled sheet metal material, the bight of said outer channel being spaced from the bight of said medial channel, said inner channel, said medial channel and said outer channel being permanently connected by a first pair of associated beads and a second pair of associated beads, said first pair of associated beads being formed in one of the legs of said outer channel and one of the legs of said medial channel, said first pair of beads interlocked and enclosing and tightly pinching the extremity of one of the legs of said inner channel, said second pair of associated beads being formed in the other of the legs of said outer channel and the other of said legs of said medial channel, said second pair of beads being interlocked and enclosing and tightly pinching the extremity of the other of said legs of said inner channel.

20. 3. The framing stock of claim 2 wherein said bight of said outer channel is provided with a reentrant step.

4. A window sash comprising a plurality of sections each including an inner channel of a relatively soft compliant material, and a medial channel and an outer channel 25 of relatively stiff resilient material in telescoped relation, said medial channel and said inner channel being permanently connected by a first pair of associated beads and a second pair of associated beads, said first pair of beads being formed in one of the legs of said outer channel and one of the legs of said medial channel, said first pair of beads being interlocked and enclosing and tightly pinching the extremity of one of the legs of said inner channel, said second pair of associated beads being formed in the other of the legs of said outer channel and the other of 30 said legs of said medial channel, said second pair of beads being interlocked and enclosing and tightly pinching the extremity of the other of said legs of said inner channel, and the latter said channel serving as a weather-proofing and shock-absorbing seal to snugly engage an edge and adjacent edge margins of a window pane.

45. 5. The window sash of claim 4 wherein the bight of said outer channel is spaced from the bight of said medial channel, and said sections are connected by brackets one of the arms of which extends into said outer channel between said bight of said outer channel and said bight of said inner channel.

6. The window sash of claim 4 wherein said sections are integral and separated by notches.
